US0D1056827S

(12) **United States Design Patent** (10) **Patent No.:** **US D1,056,827 S**
(45) **Date of Patent:** **** Jan. 7, 2025**

(54) **CHARGER**

(71) Applicant: **Polar Electro Oy**, Kempele (FI)

(72) Inventors: **Olli Komulainen**, Kempele (FI); **Lauri Lumme**, Kempele (FI)

(73) Assignee: **Polar Electro Oy**, Kempele (FI)

(**) Term: **15 Years**

(21) Appl. No.: **29/946,142**

(22) Filed: **Jun. 6, 2024**

(57) **CLAIM**

The ornamental design for a charger, as shown and described.

DESCRIPTION

FIG. 1 is a first side view of the charger;

FIG. 2 is a second side view of the charger;

FIG. 3 is a first end view of the charger;

FIG. 4 is a second end view of the charger;

FIG. 5 is a top view of the charger;

FIG. 6 is a bottom view of the charger; and,

FIG. 7 is an isometric top view of the charger.

In the drawings, the broken lines depict portions of a charger that form no part of the claimed design.
